UNITED STATES PATENT OFFICE.

JOHN G. LE PERE, OF DECATUR, ILLINOIS, ASSIGNOR TO U. S. MANUFACTURING CORPORATION, OF DECATUR, ILLINOIS, A CORPORATION OF ILLINOIS.

HANDLE CONSTRUCTION.

Application filed January 6, 1925. Serial No. 823.

This invention relates to improvements in handle constructions and is particularly directed to a method of securing wooden, composition, or similar handles to household articles or utensils such as fly swatters, corn poppers, carpet beaters, and the like, and the principal object of the invention is a new and improved construction whereby a gripping member is permanently and securely 10 and readily attached to a handle member itself composed of wire or rod.

Another object of this construction is the provision of such an arrangement whereby a wire handle member composed of two 15 strands of wire or rod are securely and permanently inserted and locked within a gripping member.

To the accomplishment of the foregoing and such other objects as may hereinafter 20 appear this invention consists in the construction, combination and arrangement of parts hereinafter described and then sought to be defined in the appended claims.

In the drawings—

25 Figure 1 represents a perspective view of a fly swatter having a handle construction coming within my invention.

Figure 2 is a longitudinal section through the gripping member of this handle construction and showing the end parts of the handle itself in position within the gripping member.

Referring now to the drawing, the numeral 1 designates a fly swatter which has a metallic handle member 2, this handle member being formed of two straight parallel strands of wire or rod extended parallel to each other and having secured on the end thereof a gripping member 3. This gripping member may be of wood, composition or other suitable material, though wood is the preferred material and is provided with the elongated socket or recess 4, adapted to receive the ends of the handle member 2.

45 The ends of the handle member 2 are cut at uneven lengths (see Figure 2 of the drawing), the longer one 5 being bent or curved and extending some distance beyond the end of the shorter one 6.

50 The straight parallel strands or parts are in contact throughout the entire length of the shorter part and they provide a solid metallic shank throughout the entire length of the said shorter part. The diameter of the socket or recess is less than the combined

diameters of the two thicknesses or strands of wire or rod so that when the handle is forced into the gripping member, the curved portion of the longer member acts as a wedge and forces the material of the gripping member slightly back by compression. In other words, it jams its way into the socket or recess which results in wedging the wires tightly within the socket or recess. This wedging action binds the two parts of the 60 handle firmly within the socket or recess, which results in a very secure attachment of the parts together.

While the curved end of the longer member 5 of the handle member extends beyond 70 the end of the shorter member 6, it does not extend far enough to touch the opposite side of the recess or socket in the gripping member and it is this construction and operation of the curved end which is very material in 75 this construction and invention. If the wires were cut off even the sharp edges would cut their way in in assembling and the gripping member would, therefore, be loose on the handle, whereas having the curved 80 longer end shown it acts, as above stated, as a wedge slightly compressing and forcing the material of the gripping member back and this material, being somewhat resilient, exercises pressure so as to securely hold the 85 gripping member on the handle.

What I claim is:—

1. In combination, a handle member and a gripping member, the handle member being composed of two straight parallel parts of 90 wire arranged in contact throughout the entire length of one of the parts to provide a solid shank within the gripping member, one part being longer than the other and extended at an angle across the end of the shorter part 95 to present an inclined entering surface forming a wedge, said gripping member being formed with a socket less in diameter than the combined diameters of the two wire parts, said two parts being forced into and 100 wedged within said socket, the extended end of the longer part terminating short of the opposite side of the shorter part and arranged out of contact with the wall engaged by the said shorter part so as not to interfere 105 with the insertion of the handle member within the gripping member.

2. In combination, a handle member and a gripping member, the handle member being composed of two parts of wire, one part be- 110

ing longer than the other, the end of the longer part being bent or curved over the end of the shorter part and terminating short of the opposite side of the shorter part, 5 said gripping member being formed with a socket less in diameter than the combined diameters of the two wire handle parts, said two parts being forced into said socket, said curved end of the longer part compressing

the material of the gripping member upon 10 insertion and the two parts of the handle member being securely held within the socket by frictional engagement with the walls thereof only.

In testimony that I claim the foregoing, I have hereunto set my hand this 27th day of December, 1924.

JOHN G. LE PERE.
